UNITED STATES PATENT OFFICE.

J. ERNEST MILLER, OF PITTSBURG, PENNSYLVANIA.

DESIGN FOR A BEER-MUG.

Specification forming part of Design No. 6,506, dated March 18, 1873.

To all whom it may concern:

Be it known that I, J. ERNEST MILLER, of Pittsburgh, in the county of Allegheny and State of Pennsylvania, have invented a Design for "Beer-Mug," of which the following is a specification:

The nature of my design is fully represented in the accompanying drawing, to which reference is made.

Figure 1 is a side elevation of the beer-mug. Fig. 2 is a vertical section of the same. Fig. 3 is a transverse section of the beer-mug at line *y* of Fig. 1.

A represents the plain portion of the mug, and B its handle. C represents the ornament-

al base, the periphery of which is provided with a series of oval-shaped concavities, D. The under side of the base C is made concave, as indicated at *e* in Fig. 2.

The distinctive character of my design is found in its general contour and the ornamental base and handle.

What I claim as of my invention is—

A design for beer-mug having the contour and ornamentation substantially as hereinbefore described.

J. ERNEST MILLER.
